UNITED STATES PATENT OFFICE.

CHESTER A. IORNS, OF ST. LOUIS, MISSOURI.

STOPPER.

1,203,349.

Specification of Letters Patent. Patented Oct. 31, 1916.

Application filed November 26, 1915. Serial No. 63,610.

To all whom it may concern:

Be it known that I, CHESTER A. IORNS, a citizen of the United States, residing at the city of St. Louis, in the State of Missouri, 5 have invented certain new and useful Improvements in Stoppers, of which the following is a specification.

This invention relates to stoppers for bottles and the like and, more particularly, 10 to stoppers adapted to form a fluid tight closure for the opening or mouth of receptacles or the like in association with which it may be applied.

It has for its object to provide a closure 15 of the character described of cheap and simple construction which may be readily applied in association with the decanting or other openings of receptacles and the like whereby said openings may be quickly, conveniently, simply and effectively closed and sealed, and, when so closed and sealed, may 20 with like facility and convenience be unsealed and opened.

Another object is to provide a closure of 25 the character described having resilient means adapted to be distended laterally under pressure to form substantially fluid tight joints with adjacent lateral walls in an opening on which the device is applied.

30 Another object is to provide a closure of the character described having a tapping outlet wherethrough the contents of a receptacle may be discharged without removing the closure of this invention from the opening of the receptacle or the like.

Further this invention consists of the construction, arrangement, and combination of parts hereinafter more particularly described and pointed out in the claims.

40 The closure heretofore usually provided for a rubber water bottle, for instance, comprises a screw-threaded casing open at both ends and mounted in the neck of said bottle and a screw-threaded plug having a resilient 45 washer at its inner end adapted to seat on a flange borne by said casing when said plug is screwed home in said casing. This character of closure requires that the plug be revolved on its axis a number of times in 50 screwing same to closing and sealing position or in unscrewing same to open position, each of which operations requires a relatively

long time, and, moreover, the screw-threads of both the casing and the plug being exposed when the plug has been removed same 55 are liable to be damaged and the closure rendered useless as an effective device.

An advantage of the closure embodying the present invention is that the plug thereof may be applied in closing and sealing position or removed from said position by a simple twisting movement whereby the adjusting finger piece of said plug is caused to turn only about one quarter of a turn on its axis, and, moreover the exposed screw-threads of the device heretofore employed are avoided thus providing a more durable closure requiring less time and care in operation. Further the plug of the closure embodying the present invention may, if desired, be applied in connection with the screw-threaded casing of the closure heretofore mounted on water bottles, and the damaging of said screw-threads will not in any way affect the effective operation of the 70 plug of the closure of this invention, said screw-threads being superfluous for the purposes of this invention but not interfering therewith.

80 In the accompanying drawings forming part of this specification wherein like numbers of reference denote like parts wherever they occur, Figure 1 is a fragmentary view of an ordinary water bottle, the neck portion thereof being shown in cross-section with a closure embodying the present invention applied thereon in closing and sealing position, the plug of said closure being shown in plan elevation and the casing mounted in the neck of the bottle being 85 shown in cross-section; Fig. 2 is a cross-sectional view on an enlarged scale of the plug and casing of the closure of this invention removed from association with the opening of a receptacle or the like and shows the details of construction of the device, the plug being in unsealed position; Fig. 3 shows the resilient means of the plug in laterally distended and sealing position under pressure applied by manipulating the finger piece; Fig. 4 is a view partly in plan and partly in section showing a fragment of a pneumatic tire with the usual valve controlled charging stem and illustrating the use of the 90 95 100

closure embodying the present invention as applied as a closure for the end of said stem; and Fig. 5 is a cross-sectional view of a modified form of the closure embodying the present invention applied to a bottle as a tap plug for the contents thereof.

A hollow casing 1 open at both ends and bearing an inwardly turned flange 2 at one end may be provided with an outwardly turned flange 3 borne by the other end of the casing, said casing being adapted to fit snugly in the neck of a water bottle 4, or of any other bottle, such for instance as the neck of a champagne bottle 5 (Fig. 5), or 10 in the opening of any other receptacle, with the inwardly turned flanged portion 2 depending in the bottle or other receptacle, as shown in Figs. 4 and 5 and with the outwardly turned flange engaging a shoulder 6 15 of water bottle 4 or engaging the outer edge of the mouth of the bottle 5 as illustrated in the one case in Fig. 4 and in the other in Fig. 5, and, if desired, said casing may be secured in position by any suitable means 20 such, for instance, as by means of being cemented to the adjacent sides of the neck of bottle 4 or bottle 5. When the closure embodying the present invention is used in connection with the valve-controlled charg- 25 ing tube 7 (Fig. 4) of a pneumatic tire 8, inwardly turned flange 2 may be mounted on and secured to outwardly turned flange 9 borne by the end of tube 7 and the outwardly turned flange 3 may be omitted the 30 edge of the end from which said flange has been omitted being if desired, flared slightly as shown at 10 in Fig. 4.

The plug or stopper of the closure of this invention comprises a pair of plates 11 and 40 12 with a pair of resilient members 13 and 14 borne therebetween, said plates and said resilient members being mounted on a stem 15, said stem being adapted to extend through said plates and said members and bearing another resilient member 16 beyond plate 12, the other end of said stem having a screw-threaded portion 17 adapted to extend outwardly beyond plate 11, on which screw-threaded portion, a screw-threaded 45 nut or block 18 is operatively mounted, a rivet head 19 or the like borne by the outwardly protruding end of stem 15 being adapted to prevent said nut or block from slipping off of or being removed from said stem and becoming lost or misplaced in use, and for the sake of compactness of construction the end of the screw-threaded opening of said nut or block adjacent said rivet head 19 or the like may be countersunk as best 50 seen at 20 in Fig. 3. Plate 11 which is adjacent to nut or block 18 is loosely mounted on stem 15 and may be formed integrally with said nut or block, but is preferably made separately therefrom, as shown in the 55 drawings and best seen in Fig. 2. The other

plate 12 may be rigidly mounted on said stem and may be supported by flange 21 borne by stem 15, which flange may be formed integrally with said plate 12 or separately therefrom, or, if desired, plate 12 may 60 itself be a flange borne by said stem, in which case flange 21 may be omitted. Resilient member 16 mounted on stem 15 below plate 12 may be supported in position between said flange 21 and a second flange 22 65 borne by the adjacent end of stem 15 as shown in the drawings. The edges of the pair of adjacent resilient members 13 and 14 may be oppositely beveled, as shown in Fig. 2, and the outer edge of resilient member 16 may be beveled as, also, shown in said Fig. 2, said resilient members being made of any suitable material, such, for instance, as rubber and being of such dimensions as to permit them to be readily inserted into casing 1 in the position and the relation of parts shown in Fig. 2 with resilient member 16 resting upon flange 2 of said casing. Nut or block 18 may be provided with any suitable grasping or manipulating means, 70 such, for instance, as ring 23 (Figs. 1 to 4, inclusive) or butterfly finger pieces 24, Fig. 5.

In operation, casing 1 having been mounted in the opening of a receptacle in any suitable manner, such, for instance, as in the manner in which said casing is shown in the drawings to be mounted in the neck of bottle 4, bottle 5, or on the end of pneumatic tire charging tube 7, the plug of the closure 80 of this invention may be inserted into said casing in the position shown in Fig. 2 and, by grasping ring 23 or butterfly finger pieces 24 firmly and pressing said resilient member 16 firmly against said flange so that it will 85 impinge upon said flange to hold stem 15 against rotation on its axis and then by a simple twisting movement of said ring 23 or butterfly finger pieces 24, block or nut 18 will be caused to move along the screw-threaded portion 17 of stem 15, and plate 11 being loosely mounted on said stem will 90 be pushed or pressed toward plate 12 as said block or nut engages said plate 11, whereby the pair of resilient members 13 and 14 will 95 be compressed between said plates and will distend laterally as shown in Fig. 3, thus causing the edges of said pair of resilient members to form substantially fluid tight joints with the adjacent lateral wall of said 100 casing, and, also, the portions of said resilient members adjacent stem 15 will be distended laterally against said stem so that no fluid can pass the joints formed by the closure of this invention when the plug 105 thereof is in closing and sealing position just described. Moreover, the plug will be very firmly held in said sealing position by means of said resilient members held distended under the pressure of screw-threaded 110

block or nut 18 moved to an appropriate position therefor on the screw-threaded portion of stem 15.

In practice it has been found that about a quarter of a turn of nut or block 18 will cause the plug of this invention to assume the sealing position shown in Figs. 1, 3, 4, and 5, the unsealing of said plug being accomplished by causing said nut or block 10 to turn about a quarter of a turn in the reverse direction.

A suitable construction to adapt the plug of the closure of this invention as a tap plug is shown in Fig. 5, wherein the solid stem 15 shown in Figs. 1 to 4, inclusive, has been omitted and tube 25 substituted therefor, said tube bearing flanges 21 and 22 adjacent its inner end and being provided with screw-threaded portion 26 on its outer end, 20 plates 11 and 12 with resilient members 13 and 14 therebetween, resilient members 16, and nut or block 18 being mounted on tube 25 in a manner similar to that in which said parts are mounted on stem 15, as shown in 25 the drawings. A faucet 27 or the like may be attached to the end of the screw-threaded portion of said tube, as shown in Fig. 5, through which faucet the flow of the contents of bottle 5 through tube 25 may be 30 controlled. The operation of inserting the tap plug shown in Fig. 5 to sealing position and removing same from that position is similar to the operation of inserting the solid stem plug, shown in Figs. 1 to 4, inclusive, to and removing same from sealing 35 position and has been hereinabove described. A closure embodying this invention provided with a tap plug, as shown in Fig. 5, and used in connection with a faucet 40 27 or the like may be applied with great advantage in connection with a champagne bottle, when it is desired to draw only a portion of the champagne from the bottle at greater or less intervals apart and preserve 45 the portion remaining in the bottle in effervescent condition. In such cases, the cork of the bottle having been drawn, a closure embodying this invention and shown in said Fig. 5 may be arranged in position in association with the neck of said bottle, as shown 50 in said Fig. 5, and the contents of the bottle drawn off through faucet 27 in such quantities and at such intervals as it is desired to use same. The tubular stem tap plug 55 shown in Fig. 5 may, also, be used to great advantage in connection with water bottle 4 when said bottle is used as part of the well known fountain syringe, in which case an end of the flexible tube of said syringe may 60 be attached to the discharge end of faucet 27, or, if desired, said faucet may be omitted and said end of said flexible tube may be attached directly to the discharge end of tubular stem 25.

65 An advantage of applying the closure of

this invention to the charging tube of a pneumatic tire shown in Fig. 4 is that by means of said closure air will not escape from the tire even should the usual valve-control mounted in said charging tube 70 become inoperative and leak. In the drawings, a pair of resilient members 14 and 13 are shown mounted between plates 11 and 12, but it is, of course, understood that there may be more than two of such resilient members so mounted or that there may, if desired be only one resilient member of a suitable thickness and material mounted between said plates. 75

Various changes in the construction, arrangement, and combination of parts may be made without departing from the nature and spirit of the present invention.

I claim:

1. A stopper comprising a casing and a removable plug, said plug comprising a stem, a resilient member rigidly connected to the lower end of the stem and adapted to engage the lower end of said casing, a plate loosely mounted upon said stem and held in 85 spaced relation with said resilient member, a pair of resilient members mounted upon said plate, and means for applying pressure to said resilient members for distending the same laterally for the purpose set forth. 95

2. A stopper comprising a cylindrical casing and a removable plug adapted to rest therein, said plug comprising a stem, a pair of truncated conical-shaped members loosely mounted upon said stem, the bases of said 100 truncated conical-shaped members lying adjacent to each other, and means adapted to distend said truncated conical-shaped members laterally whereby the lateral surfaces of their base portions will be seated against 105 the inner wall of said casing.

3. A stopper comprising a casing and a removable plug, said plug comprising a stem, a resilient member rigidly connected to the lower end of the stem and adapted to engage 110 the lower end of said casing, a plate borne by said stem and in spaced relation with said resilient member, resilient means loosely mounted on said stem adjacent to said plate, and means for applying pressure to said resilient means for distending the same laterally for the purpose set forth. 115

4. A stopper comprising a casing and a removable plug, said plug comprising a stem, a resilient member rigidly connected 120 to the lower end of the stem and adapted to engage the lower end of said casing, a plate rigidly borne by said stem in spaced relation with said resilient member, a second plate loosely mounted on said stem opposite 125 said rigidly-mounted plate, resilient means mounted on said stem between said two plates, and means for applying pressure to said resilient means for distending the same laterally for the purpose set forth. 130

5. A stopper comprising a casing and a removable plug, said plug comprising a stem, a resilient member rigidly connected to the lower end of the stem and adapted to engage the lower end of said casing, a plate borne by said stem in spaced relation with said resilient member, resilient means loosely mounted on said stem adjacent to said plate,

and means for applying pressure for distending said resilient means laterally and 10 for engaging said resilient member with the lower end of said casing for the purpose set forth.

In testimony whereof I hereunto affix my signature.

CHESTER A. IORNS.
